[57] **CLAIM**

I claim the ornamental design for a portable toilet seat for a child, as shown and described.

DESCRIPTION

FIG. 1 is a top, front and side perspective view of the portable toilet seat for a child embodying the design of the present invention;

FIG. 2 is a front elevational view thereof;

FIG. 3 is a rear elevational view thereof;

FIG. 4 is a right side elevational view thereof; the left side being a mirror image of the right side;

FIG. 5 is a top plan view thereof; and,

FIG. 6 is a bottom view thereof.

FIG. 1.

FIG. 6.

FIG. 2.

FIG. 3.

FIG. 5.

FIG. 4.
